Kameron D. Kelly(57) **CLAIM**

The ornamental design for a loader machine loader arm as shown and described.

DESCRIPTION

FIG. 1 is a top front left perspective view of a loader machine loader arm showing our new design in an environment in which it may be used;

FIG. 2 is a bottom rear right perspective view thereof showing our new design in an environment in which it may be used;

FIG. 3 is a front right perspective view thereof;

FIG. 4 is a rear left perspective view thereof;

FIG. 5 is a front elevation view thereof;

FIG. 6 is a left side elevation view thereof;

FIG. 7 is a rear elevation view thereof;

FIG. 8 is a right side elevation view thereof;

FIG. 9 is a top plan view thereof; and,

FIG. 10 is a bottom plan view thereof.

In the drawings, the broken lines depict portions of the loader machine loader arm that form no part of the claimed design, and the additional broken lines in FIGS. 1 and 2 depict a loader machine environment that forms no part of the claimed design.
